UNITED STATES PATENT OFFICE

163,453

ROUND BOTTLE

Brooks D. Fuerst, Sylvania, Ohio

Application December 8, 1950, Serial No. 13,336

Term of patent 14 years

(Cl. D58—8)

To all whom it may concern:

Be it known that I, Brooks D. Fuerst, a citizen of the United States of America, residing at Sylvania, in the county of Lucas, and State of Ohio, have invented a certain new, original, and ornamental Design for a Round Bottle, of which the following is a specification, reference being had to the accompanying drawing, forming a part hereof.

Fig. 1 is an elevational view of a round bottle showing my new design, and

Fig. 2 is a top plan view thereof.

I claim:

The ornamental design for a round bottle, as shown.

BROOKS D. FUERST.
